UNITED STATES PATENT OFFICE

161,195

COMBINED VASE AND CARD HOLDER

Mary Mortimer, Lansing, Mich.

Application March 9, 1950, Serial No. 8,430

Term of patent 7 years

(Cl. D29—28)

To all whom it may concern:

Be it known that I, Mary Mortimer, a citizen of the United States of America, residing in the city of Lansing, county of Ingham, and State of Michigan, have invented a new, original, and ornamental Design for a Combined Vase and Card Holder, of which the following is a specification, reference being had to the accompanying drawing, forming part thereof, wherein:

Figure 3 is an end elevational view of the embodiment of my new design; and

I claim:

The ornamental design for a combined vase and card holder, as shown.

MARY MORTIMER.
